UNITED STATES PATENT OFFICE.

JAMES N. BRADFORD AND AMOS S. PARKE, OF BAY CITY, MICHIGAN.

PUMP-VALVE.

SPECIFICATION forming part of Letters Patent No. 248,282, dated October 18, 1881.

Application filed February 1, 1881. (Model.)

To all whom it may concern:

Be it known that we, JAMES N. BRADFORD and AMOS S. PARKE, of Bay City, in the county of Bay and State of Michigan, have invented certain new and useful Improvements in Pump-Valves; and we do hereby declare that the following is a full, clear, and exact description of the invention, which will enable others skilled in the art to which it appertains to make and use the same, reference being had to the accompanying drawings, which form a part of this specification.

Figure 1 is a side view of the valve, and Fig. 2 is a vertical sectional view of our improved valve and pump chamber.

Similar letters of reference indicate corresponding parts in both figures.

This invention relates to pump valves or pistons for salt and other wells; and it consists in certain improvements in the construction of the same and of the pump-chamber, which will be hereinafter fully described, and particularly pointed out in the claims.

In the drawings hereto annexed, A represents the valve-stem, which consists of a cylindrical body, provided near its lower end with a flanged annular rim, B, below which it is threaded, as shown at C. Below the thread C the guide-stem D for the valve is formed, as shown.

Near its upper end the valve-stem is threaded, as shown at E, above which point provision is made, as shown at F, for the attachment of the pump-rods or of an upper hollow chamber, to be hereinafter described.

G is a leather packing-ring, which is inclosed by a ring or band, H, having upon its inner side a stud, I, fitting in a vertical slot, J, in the ring G, to which it is in this manner connected. The band H is provided with a vertical interlocking joint, K, which, while permitting it to expand, prevents leakage between the piston and the pump-chamber.

The upper threaded portion, E, of the valve-stem is made bulging, as shown, and is formed with a shoulder, L, between which and the rim B, near the lower end of the valve-stem, the band G is accommodated, the ring or band H being fitted between the flange M of rim B and a collar, N, screwed upon the threaded portion E of the valve-stem.

The lower part of the piston consists of the valve-chamber O and a cup, P, which latter is of less diameter than the piston, so that a space, Q, shall be left between the walls of the pump-chamber and the said cup, which is closed at the lower end.

Between the cup P and chamber O are a series of perforations, R, through which the fluid is admitted into the valve-chamber, which latter is provided with a rim or flange, S, overlapping and protecting the said openings.

The valve-chamber is provided with an inferior thread, T, by which it is connected to the lower threaded end, C, of the valve-stem, and it has an interior annular flange, U, which is ground to form a seat for the valve V.

The lower flanged and threaded portion, C, of the valve-stem is provided with orifices or channels W for the admission of fluid from the valve-chamber into the space X, between the valve-stem and the packing-rings G H. The upper bulging and threaded portion, E, of the valve-stem is provided with vertical grooves Y, between which and the collar N the fluid may pass up through the valve.

To the upper threaded end, E, of the valve-stem above the collar N is attached a hollow or cup-shaped top, Z, made in a single piece or in two or more sections, and provided at its upper end with a threaded nib, A', for attachment of the pump-rods. Said top is also provided with suitable openings for the passage of fluid.

B' represents the pump-chamber, which is made of cast-steel in a suitable number of sections, C', connected by screw-joints D'. It has been found practically impossible to cast a pump-chamber of sufficient length perfectly straight and true, and considerable difficulty has been experienced from this source. By forming the pump-chamber in sections, as herein shown, this difficulty may be largely or entirely overcome.

The operation of our improved pump-valve will be readily understood by those skilled in the art to which it appertains, and its advantages over those ordinarily employed are numerous. This kind of pistons or valves are generally employed in wells of great depth— frequently from twelve hundred to fifteen hundred feet—and owing to the immense pressure

of fluid, leakage between the piston and pump-chamber is an annoyance experienced as frequently as it has been found difficult to remedy in a thorough and satisfactory manner, and by 5 which a great loss of time and power has been caused.

Packing rings or bands adjusted upon a perforated valve-body and capable of being expanded in the pump-chamber by fluid pressure have been used with some degree of success. Now, it will be observed that the entire body of our improved valve is formed by the expandible ring G and its protecting expandible band H, which receive directly the entire 15 pressure of the fluid column, by which the said expandible valve-body is fitted in the pump-chamber in such a manner as to render leakage practically impossible.

The construction is simplified, only few parts 20 being employed in the make-up of the piston, and the result has been demonstrated to be highly satisfactory.

Another important feature of our improved piston is the closed contracted cup which forms 25 its lower end, and above which the fluid is admitted into the valve-chamber. On the down-stroke of the piston the fluid rushes with great force between said contracted cup and the walls of the pump-chamber, which are thereby 30 cleaned of any grit and impurities which might impede the progress of the valve and destroy the perfect fit between the piston and the pump-chamber.

We would finally invite attention to the 35 low top of the valve, to which the operating rods are attached, and which forms a protecting covering. In the event of accident or breakage the said hollow top may be detached, the operating-rods attached to the valve-stem, and 40 the operation of the pump proceed without further interruption.

Having thus described our invention, we claim and desire to secure by Letters Patent of the United States—

45 1. In a pump-piston for deep wells, the body consisting of a leather ring subject to direct fluid pressure, in combination with an expandible band or covering having vertical interlocking joints to prevent leakage, as set forth.

2. The combination of the valve-stem A, having at its lower end the annular screw-threaded and flanged rim B, and an upper bulging screw-threaded portion, E, with the flexible ring or band G, the surrounding expandible ring or band H, and the collar N, the said flanged rim 55 and the said bulging portion of the valve-stem being provided with channels for the passage of the fluid, substantially as described.

3. In a pump-piston for deep wells, the expandible body consisting of a leather ring or band having a vertical slot, in combination with an expandible ring provided upon its inner side with a stud engaging said slot, as set forth.

4. The pump-piston provided with the valve-stem, valve, valve-chamber O, and a cup, P, of less diameter than the piston, said cup being closed at its bottom, and being provided with perforations between its closed bottom and the valve-chamber, substantially as described.

5. The combination, with a pump-piston capable of being operated by the direct attachment of the pump-rods to the valve-stem, of a detachable hollow top or protecting-cap having 75 means for the attachment of the pump-rods, substantially as set forth.

6. The herein-described pump-piston for deep wells, consisting of a valve-stem provided with a flanged rim and a bulging threaded portion, an expandible body secured upon said valve-stem by a threaded collar, a valve-chamber provided with a closed contracted lower section, and a detachable hollow top or protecting cap, all combined and operating substantially as and for the purpose shown and specified.

In testimony that we claim the foregoing as our own we have hereto affixed our signatures in presence of two witnesses.

JAMES N. BRADFORD.
AMOS S. PARKE.
